DESIGN FOR A SADIRON SHELL

Russell I. Huffman, Dover, Ohio, assignor to The
Dover Manufacturing Co., Dover, Ohio, a cor-
poration of Ohio

Application March 31, 1936, Serial No. 61,878

Term of patent 7 years

To all whom it may concern:

Be it known that I, Russell I. Huffman, a citizen of the United States and a resident of Dover, in the county of Tuscarawas and State of Ohio, have invented a new, original, and ornamental Design for a Sadiron Shell, of which the following is a specification, reference being had to the accompanying drawing, forming part thereof.

Figure 1 is a perspective view of a sadiron shell showing my new design.

Figure 2 is a plan view thereof.

Figure 3 is a side elevational view thereof.

Figure 4 is a front elevational view thereof; and
Figure 5 is a rear elevational view thereof.

I claim:

The ornamental design for a sadiron shell, as
shown.

RUSSELL I. HUFFMAN.
